UNITED STATES PATENT OFFICE.

GLEN D. BAGLEY, OF GREAT NECK, NEW YORK, ASSIGNOR TO THE KEMET LABORATORIES CO. INC., A CORPORATION OF NEW YORK.

ELECTRIC VACUUM FURNACE.

Application filed April 28, 1927. Serial No. 187,949.

This invention relates to furnaces and more particularly to improvements in electrically heated vacuum furnaces of the type in which the heat chamber is sealed with mercury to permit sub-atmospheric pressure to be maintained therein.

One of the objects of my invention is to provide an electric furnace in which given temperatures may be obtained with less current than has heretofore been required. Another object of my invention is to prevent the deposition of an opaque metallic film on the walls of the heating chamber especially when the latter is constructed of glass. Another object of my invention is to provide a yieldable supporting contact for the heating elements to avoid buckling and tearing of this element. A still further object of my invention is to reduce the amount of mercury required to seal the furnace chamber.

These and other objects and the novel features of this invention will be apparent from the following description taken in connection with the accompanying drawings, in which: Fig. 1 schematically illustrates a vertical section of an electric furnace embodying this invention, certain parts being shown in elevation;

Fig. 2 is a detail sectional view of a portion of the furnace taken on the line 2—2 of Fig. 3; and

Fig. 3 is a horizontal section taken on the line 3—3 of Fig. 2.

As illustrated, the furnace comprises a steel tube 10 closed at its upper end, the upper interior of which provides a gas tight chamber 11 in which the furnacing operation is carried on. It will be understood, however, that improvements herein disclosed are also applicable to furnaces of the type shown and described in other applications, in which a glass walled furnace is disclosed. However, the metallic tube has advantages over the use of glass since the latter becomes heated and is liable to crack when suddenly cooled as by a draft. Moreover the glass may be of uneven thickness in which case the thinner portions may collapse when subjected to a high vacuum. By making the wall of metal it is possible to bring a cooling coil 20 into contact therewith, thus allowing the wall to be much closer to the resistor than is possible when glass is used, with a consequent decrease in the space to be evacuated. A suitable cooling medium, such as water, is

circulated through this coil. The tube is provided with a suitable conduit 13 for the purpose of evacuating the chamber 11. At the end of the tube suitable means 14 are provided for permitting an inspection of the interior of the furnace when a tube of opaque material is employed.

The tube 10 is sealed by disposing the lower open end below the level of a body of mercury 16 in a reservoir 17. Inside the lower end, but spaced from and desirably concentric with it, is a tube 21 of suitable insulating material, such as glass or bakelite, which extends through a fluid tight joint in the bottom of the reservoir 17 and has its lower end sealed by a closure 18 and contains a second body of mercury 30. The reservoir 17 constitutes a seal for the chamber 11, is open to the atmosphere and is of a suitable size to hold the quantity of mercury required for the mercury column when the furnace is highly evacuated. A cooling pipe 19 extends upwardly through the closure 18 and is closed at its upper end. The cooling fluid, ordinarily water, flows in through the pipe 19 and out through a pipe 22 inside the pipe 19.

The charge in the chamber 11 is electrically heated by means of a resistor 24 which is connected in series circuit with an electrical conductor 25, the cooling elements 19, and the mercury 30. The conductor 25 may be a rod or tube of metal or any conducting material suited to the current and temperature to be used. If the resistor is to be operated at a temperature above the melting point of the conductor material, water or other cooling medium may be circulated through the conductor. The legs of conductor 25 extend into opposite sides of the reservoir 17 through suitable mercury tight joints, thence up through the mercury 16 and the annular space between the tubes 12 and 21 and into the chamber 10 where they are connected by the bend 26. As shown, the conductors 25 and 19 and the respective columns of mercury through which they pass, are insulated from one another by the tube 21. If desired the lower ends of the conductor 25 may be bent under the lower edge of the tube 10 and brought up through the mercury seal 16. Current supply cables 28 and 29 may be secured to the conductors 25 and 19 respectively by suitable clamps, and rubber hose or other suitable means may

be coupled thereto for circulating cooling fluid therethrough.

The resistor 24 is adapted to surround the furnace charge and is desirably in the form of a cylinder formed by bringing together two elongated curved sheets of a refractory metal such as tungsten, molybdenum or the like. The parts of the vertical tubular resistor are rigidly held at their upper ends 10 and electrically connected to the conductor 25 by a copper clamp 31 consisting of two similar sections clamped to the legs of the conductor by bolts 32. The bend 26 may be curved so as not to obstruct the view through 15 14 into the upper end of the resistor.

The lower end of resistor 24 is clamped to a contact member 34 by a clamp 33. Member 34 dips into the mercury 30 to complete the circuit and is at least partially supported 20 by the mercury thus relieving the resistor of its weight. The height of this column of mercury is preferably great enough to act as a seal against any leaks in the closure at the bottom of the insulating tube 21.

25 Since resistor 24 is rigidly attached at its upper end only, its lower end is free to move vertically to compensate for any expansion and contraction of resistor 24 and connected parts and thus eliminates the possibility of 30 buckling or tearing the resistor through this cause. The contact 34 and the clamp 33 are cooled by the conduction of their heat to the mercury within the tube 21, whence heat is carried away by the cooling medium within 35 the tubes 19 and 22 which project into cavity 34' in the lower end of contact 34. A vent 41 for the cavity 34' provides for pressure equalization. The upper clamp 31 is kept cooled by the circulation of cooling fluid through the conductor 25 and the tube 10 is cooled by the circulation of a cooling medium through the coil 20. So cooled, the furnace can be operated at any temperature 40 up to the melting point of the resistor.

45 In order to conserve the energy required to operate the furnace I have found it advantageous to provide a nonporous metallic radiation screen 35 around the resistor 24. This radiation screen may consist of a sheet 50 iron cylinder concentric with the resistor and spaced therefrom a distance of about $\frac{1}{4}$ ". While I may insulate this screen from the resistor by suitable discs of non-contacting material, I have found it sufficient to space it from the resistor and from one of the terminals, rigidly securing it to the other terminal, preferably the lower one, in any suitable manner as by welding it to the clamp 33. The screen is desirably imperforate except for the provision of an opening 42 therein for the purpose of permitting the resistor to be observed and in order that the temperature of the latter may be measured 55 with an optical pyrometer in case the tube 10 is formed of a transparent material. I

may employ more than one screen of the type described, in which case it is evident that the openings in the several screens should be in alinement. The provision of such screens diminishes the heat radiation 70 from the resistor and results in a very considerable saving in the amount of power required. Theoretically, this saving is

$$\frac{n}{n+1},$$

75

where n is the number of concentric screens, it being assumed in this formula that the surface of each screen is approximately equal to that of the resistor itself. This radiation screen also prevents the deposition of an opaque film on the chamber wall which occurs very rapidly in a high vacuum and at high temperature, especially when a molybdenum resistor is employed. This film is especially objectionable when the chamber wall is of a transparent material. I am aware that it has hitherto been proposed to use means to prevent radiation consisting of 80 an annular graphite box filled with graphite powder; but this structure contains a large amount of gas within its pores, which is given off at the low pressures employed within the furnace, thereby making it difficult to secure a high vacuum and I have 85 found metallic radiation screens superior to such graphite screens.

In order to reduce the amount of mercury required I may employ an annular displacement member 38 between tube 21 and the stem 12, the contacting and cooling member 23 being disposed either within or without this annular member or still better in suitable vertical recesses in the side of the annular member 38, which may be of iron. This also reduces the surface of mercury subject to vaporization and lessens the amount of mercury vapor which may find its way into the furnace chamber.

100 The operation of my device is as follows:

To heat a charge to a high temperature under vacuum the seal at the tubular opening 13 is broken and the outer member 10 is freely lifted off exposing the resistor 24. The material to be heated is then placed inside the resistor in a suitable container and the outer member 10 is so replaced as to submerge its lower end in the mercury 16 thereby sealing the chamber 11. The outlet 13 is then sealed to a vacuum pump and chamber 11 is evacuated. As the air is pumped out mercury rises into the lower end of the tube 10 approaching the barometric height, but since the tubes 10 and 21 are over 30" long the mercury does not rise into the furnace chamber even with the highest vacua attainable. The degree of vacuum may be roughly estimated by the height of the mercury column in the tube 10 if this be 115 of transparent material, but in any event it 120

110

105

115

120

125

130

is accurately determined by the use of gauges connected to the tube 13. Because of the relatively small volume of the chamber 11 as compared with furnaces employing a globe-shaped heating chamber, it is possible to evacuate the chamber more quickly and perform a greater number of meltings in a given period.

When the desired degree of vacuum has been reached circulation of the cooling medium is started and suitable electric current is supplied by closing a switch in circuit with the cables 28 and 29. At the end of a period of use the current is shut off and atmospheric pressure is restored to the chamber 11 when the charge and the resistor elements have cooled sufficiently to prevent oxidation or other deleterious action. At that time the column of mercury within the tube 10 will have dropped to its level in the reservoir 17 and the tube may be lifted off giving free access to the furnace charge.

I claim:

1. An electric furnace comprising a gas tight chamber, a resistor therein, and a screen of substantially non-porous and dense material surrounding said resistor and reducing heat radiation from the latter.
2. An electric furnace according to claim 1 wherein said screen is of metal.
3. An electric furnace according to claim 1 wherein said resistor and said screen are of tubular metal and concentric.
4. An electric furnace comprising a gas tight chamber, a tubular metal resistor therein, and a tubular metal screen concentric with and surrounding said resistor, said screen being a non-current-carrying element and reducing heat radiation from said resistor.
5. An electric furnace comprising a gas tight chamber, a resistor therein, a body of mercury sealing said chamber, and a second body of mercury electrically connected to one end of said resistor and arranged to at least partially support said resistor so that the latter may freely expand and contract.
6. An electric furnace comprising a gas tight chamber, a body of mercury sealing said chamber, and second body of mercury independent of the first, and a resistor in said chamber having a contact at one end extending into and movable relative to said second body of mercury, whereby said resistor and second body of mercury are electrically connected and said resistor is free to expand and contract without distortion.
7. An electric furnace comprising a gas tight chamber, a body of mercury sealing said chamber, a hollow resistor in said chamber having a freely movable contact at one end, a conductor extending into said furnace and a second body of mercury providing an electrical connection between said resistor contact and said conductor.
8. An electric furnace according to claim 7 wherein said conductor comprises means for circulating cooling medium relatively to said second body of mercury so as to cool the latter and indirectly to cool said contact. 70
9. An electric furnace comprising a chamber having a tubular wall, a body of mercury cooperating with said wall to seal said chamber, an insulating tube within said wall, a resistor in said chamber having a contact depending into said tube, a conductor extending into said tube, and a body of mercury in said tube electrically connecting said conductor to said contact and at least partially supporting the latter and said resistor. 80
10. An electric furnace comprising a chamber having a tubular wall, a body of mercury cooperating with said wall to provide a barometric seal for said chamber, an insulating tube within and spaced from said wall, a conductor extending into said tube, a resistor in said chamber having a contact in said tube in circuit with, but freely movable relatively to said conductor, and a solid annular member in the space between such tube and wall to reduce the volume of mercury required to form a barometric seal for said chamber. 85
11. An electric furnace comprising a vertical metal tube open at its lower end and closed at its upper end to provide a furnace chamber within said upper end, a body of mercury cooperating with said lower end to provide a barometric seal for said chamber, an insulating tube projecting into said metal tube through the lower end thereof, a resistor in said chamber having a contact depending into said insulating tube, a conductor in said insulating tube and a body of mercury in said insulating tube electrically connecting said contact to said conductor. 95
12. An electric furnace comprising a chamber having a cylindrical bottom portion, a heating element within said chamber, electrically insulated concentric columns of mercury within said bottom portion, the outer column forming a barometric seal for said chamber and the inner column serving as means for partially supporting and conducting current to one of the terminals of said heating element. 100
13. An electric furnace comprising a tubular wall of substantially uniform diameter providing a furnace chamber therein adjacent one end, means cooperating with the other end of said wall to seal said chamber, a resistor in said chamber, and means for cooling said wall. 110
14. An electric furnace according to claim 13 wherein such wall is of metal and such cooling means comprises a cooling coil in contact with said wall. 125

In testimony whereof, I affix my signature.

GLEN D. BAGLEY.
